WIRE TYING MECHANISM

Carl Floyd Ott and Jud T. Ott, Yuma, Ariz.

Application October 16, 1950, Serial No. 190,348

8 Claims. (Cl. 140—119)

1

This invention relates to new and useful improvements in wire tying or splicing devices and the primary object of the present invention is to provide a wire tying mechanism for use in tying the ends of wire together on hay balers and more specifically the three-wire, heavy-duty, Case baler.

Another important object of the present invention is to provide a wire tying mechanism including a rotatable gear having a slot for receiving a pair of wires or the ends of a wire and a novel and improved means for gripping the wire or wires so that as the gear is rotated the wire or wires will be twisted.

A further object of the present invention is to provide a wire tying mechanism including a plurality of wire twisting members and a mechanism for simultaneously ejecting wires from all of the twisting members.

A still further aim of the present invention is to provide a portable manually operated wire tying mechanism for baling machines that is simple and practical in construction, strong and reliable in use, efficient and durable in operation, inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of the present invention;

Figure 2 is an enlarged fragmentary side elevational view of Figure 1;

Figure 3 is an enlarged fragmentary rear elevational view of Figure 1 and with parts broken away;

Figure 4 is an enlarged transverse horizontal sectional view taken substantially on the plane of section line 4—4 of Figure 1;

Figure 5 is a fragmentary perspective view showing the tying member, the operating bar for the tying member, the retainers for wire engaged with the tying member, and the ejector bars;

Figure 6 is an enlarged vertical sectional view taken substantially on the plane of section line 6—6 of Figure 1;

Figure 7 is a vertical sectional view taken substantially on the plane of section line 7—7 of Figure 3; and

Figure 8 is a sectional view taken substantially on the plane of section line 8—8 of Figure 4.

2

Referring now to the drawings in detail, wherein for the purpose of illustration, there is disclosed a preferred embodiment of the present invention, the numerals 10 and 12 Fig. 3, represent a pair of elongated back-to-back angle iron members that are connected together by any suitable number of cross straps. The opposing flanges 16 and 18 of the members 10 and 12 are joined by bolts 20 that rotatably support ball bearing roller units 22 which are positioned between the flanges 16 and 18.

Slidably mounted on the roller units 22, between the flanges 16 and 18, is an elongated rack bar or actuating member 24 that extends between pairs of bearings 26 Fig. 4. The bearings 26 are removably secured to the members 10 and 12 by fasteners 28 Fig. 6, and the bearings 26 include inner and outer portions that are secured together by bolts 30. The bearings are provided with axial bores 32 and the outer portions of the bearings are formed with elongated openings or slots 34 that intersect the bores 32.

A wire tying member 36 is associated with each pair of bearings and the members 36 Fig. 5, each include a tube or hub 38 having a driven gear or pinion 40 fixed thereto intermediate its ends. The gears 40 are provided with radial or inwardly extending slots 42 that intersect longitudinal slots or splits 44 in the tubes 38. The gears 40 mesh with the rack bar 24 and the ends of the tubes 38 are rotatably supported in the bores 32 of the bearings 26 which may be, for example, in the form of bronze pillow blocks.

Means is provided for sliding the rack bar 24 in order to simultaneously rotate the gears 40. This means consists of a platform 46, Figs. 1 and 2, that is mounted on the members 10 and 12 at their upper ends. A pair of arms 48 rise from the platform 46 and support bearings 50 through which a shaft 52 extends to support a handle 54. A driven gear 56 is keyed on the shaft 52 between the bearings 50 and meshes with the upper end of the rack bar 24.

Means is provided for holding wires within the tubes 38 and the slots 42 of the gears 40. This means in the present instance consists of pairs of channel shaped guides or supports 56, Figs. 5 and 8, that are fixed by welding or the like to the members 10 and 12. The guides 56 are disposed at the ends of the tubes 38 and support pivots 58 that extend through clamping arms 60 having upwardly curved outer end portions 62.

The arms 60 are provided with openings or ball seats 64 that receive balls 66. Coil springs 68 are biased between the balls 66 and the upper walls of

the guides 56 and urge the balls partially through the openings 64 and against plates 70 constituting the bottom walls of the guides. The plates 70 are provided with downwardly and outwardly inclined extensions 72. The guides 56 extend transversely of the tubes 38 and the pivots 58 are spaced parallel to the tubes 38 to permit the arms 60 to clamp wires against the plates 70 as other portions of the wires are rotated and twisted by the members 36.

Means is provided for ejecting wires for the tubes 38 and the slots 42 in the gears 40. This means comprises upper and lower rods or bolts 74 and 76, Figs. 2, 3, and 4, slidably carried by the members 10 and 12. The bolts 74 are connected by an upper cross strip 78 and the lower bolts 76 are connected by a lower cross strip 80. A pressure plate 82 is terminally secured to the strips 78 and 80. Coil springs 84 surround the bolts 74, 76 and are biased between the strips 78, 80 and the members 10, 12 to yieldingly urge the plate 82 from the rear of the members 10 and 12.

Longitudinally extending ejector bars 86 and 88, Fig. 5, parallel the rack bar 24. The upper ends of the bars 86 and 88 are secured to the forward ends of the bolts 74 and the lower ends of the bars 86 and 88 are secured to the forward ends of the bolts 76.

The bars 86 and 88 are normally urged against the members 10 and 12 by the springs 84 and are located between the ends of the tubes 38 and the guides 56. The bars 86 and 88 also extend transversely of and past all of the tubes 38 so that as the plate 82 is forced against the flanges 16 and 18, the bars 86 and 88 will be moved laterally across the tubes 38 to force wires from the tubes 38 and the gears 40 by way of the slots 44 and 42.

Inasmuch as the invention is specifically constructed for use with a three-wire, heavy-duty, Case baler there are provided three of the tying members 36. However, more than three or less than three tying members may be used.

In practical use of the invention, the parallel ends of a wire or two wires W are extended into the tubes 38 by placing the wires in the openings 34, slots 44 and 42. The wires are also extended under the arms 60 and against the plates 70.

As the gear 56 is rotated, the rack bar 24 will slide and cause the gears 40 to rotate and since the arms 60 hold the wires tight, only the portions of the wires gripped by the gears 40 and between the arms 60 will rotate, to be twisted as shown in Figure 5.

After the wires have been twisted, the plate 82 is forced toward the flanges 16 and 18 and the bars 86 and 88 will force the wires from the tubes 38 and gears 40, it being understood that the slots 42 and 44 will be in registry with the openings 34 as the ejector bars are actuated. The sliding of the rack bar may be limited by an enlarged tooth T on the gear 56 so that the slots 42 and 44 will be in registry with the openings 34 after the gears 40 have been rotated sufficiently to twist the wire.

A roller R is mounted on the lower end of one of the angle iron members for the mounting on a track along side of a baler.

In view of the foregoing description taken in conjunction with the accompanying drawings it is believed that a clear understanding of the construction, operation and advantages of the device will be quite apparent to those skilled in this art.

A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed 10 as new is:

1. A wire splicing device for use with a baler for tying the binding wires about the resulting bales comprising an elongated frame, a toothed rack extending lengthwise of said frame, means for reciprocating said rack, mechanism for guiding said rack for movement lengthwise of said frame, a plurality of wire tying members spaced longitudinally of said frame and each including a driven gear engaged with said rack on one side of said frame for rotation by reason of lengthwise movement of said rack, each of said driven gears having oppositely axially projecting hubs, bearings on said frame in which said hubs are journaled, said driven gear, said hubs and said bearings providing notches registering in one position of said gears and hubs for receiving a plurality of parallelly arranged wires, means for locating said rack and gears with said notches in registering position, wire holding means fixed in relation to said frame spaced outwardly from the bearings beyond the ends of the notched hubs and arranged to hold said wires for twisting between said holding means, and wire extracting means shiftable relatively to said frame, having portions disposed to engage wires between said bearings and said wire holding means to force them in a direction to remove them from said notches, and said wire extracting means having a manually engageable actuating portion on the other side of said frame as related to said driven gears, said hubs, said bearings and said wire holding means.

2. A wire splicing device for use with a baler for tying the binding wires about the resulting bales comprising a frame adapted to be supported on a baler, a plurality of wire tying members on the side of said frame toward said baler, each including a driven gear having an axially projecting hub, a bearing on said frame in which said hub is journaled, said driven gear, said hub and said bearing providing notches registering in one position of said gear and hub and opening toward said baler for receiving a plurality of parallelly arranged wires, means for locating said gears with said notches in registering position, wire holding means fixed in relation to said frame spaced outwardly from the bearings beyond the ends of the notched hubs and arranged to hold said wires for twisting between said holding means, and wire extracting means shiftable relatively to said frame, having a portion disposed to engage a wire between each bearing and the adjacent wire holding means to force it in a direction to remove it from said notch, and said wire extracting means having a manually engageable actuating portion on the other side of said frame as related to said driven gear, said hub, said bearing and said wire holding means.

3. A wire splicing device for use with a baler for tying the binding wires about the resulting bales comprising a frame adapted to be supported on a baler, a plurality of wire tying members on the side of said frame toward said baler, each including a driven gear having an axially projecting hub, a bearing on said frame in which said

hub is journaled, said driven gear, said hub and said bearing providing notches registering in one position of said gear and hub for engaging a plurality of parallelly arranged wires, means for locating said gears with said notches in registering position, wire holding means fixed in relation to said frame spaced outwardly from the bearings beyond the ends of the notched hubs, and each including a guide plate and a clamping portion yieldingly urged against said plate for holding said plurality of wires against inadvertent displacement from said wire holding means and for twisting between said wire holding means and said driven gears, and wire extracting means shiftable relatively to said frame, having a portion disposed to engage a wire between each bearing and its wire holding means to force it in a direction to remove it from said notch, and said wire extracting means having a manually engageable actuating portion on the other side of said frame as related to said driven gear, said hub, said bearing, and said wire holding means.

4. A wire splicing device for use with a baler for tying the binding wires about the resulting bales comprising a frame adapted to be supported on a baler, a plurality of wire tying members on the side of said frame toward said baler, each including a driven gear having an axially projecting hub, a bearing on said frame in which said hub is journaled, said driven gear, said hub and said bearing providing notches registering in one position of said gear and hub for reception of a pair of parallelly arranged wires, means for locating said gears with said notches in registering position, wire holding means fixed in relation to said frame spaced outwardly from the bearings beyond the ends of the notched hubs, and each including a guide plate and a pivoted clamping arm of a length to engage said pair of wires, a detent ball seated in the arm and yieldingly urged against said plate by pivoting of said arm for retaining said wires against inadvertent displacement from said holding means, and wire extracting means shiftable relatively to said frame, having a portion disposed to engage a wire between said bearing and said wire holding means to force it in a direction to remove it from said notch, and said wire extracting means having a manually engageable actuating portion on the other side of said frame as related to said driven gear, said hub, said bearing, and said wire holding means.

5. A wire splicing device for use with a baler for tying the binding wires about the resulting bales comprising a frame adapted to be supported on a baler, a plurality of wire tying members on the side of said frame toward said baler, each including a driven gear having an axially projecting hub, a bearing on said frame in which said hub is journaled, said driven gear, said hub and said bearing providing notches registering in one position of said gear and hub for receiving a pair of parallelly arranged wires, means for locating said gears with said notches in registering position, wire holding means fixed in relation to said frame spaced outwardly from the bearings beyond the ends of the notched hubs and adapted to hold said wires for twisting between said wire holding means and said driven gear, and wire extracting means shiftable relatively to said frame, having a portion disposed to engage a wire between said bearing and said wire holding means to force it in a direction to remove it from said notch, and a guide portion slidably rela-

tively to said frame, and said wire extracting means having a manually engageable actuating portion fixed to said guide portion on the other side of said frame as related to said driven gear, said hub, said bearing, and said wire holding means.

6. A wire splicing device for use with a baler for tying the binding wires about the resulting bales comprising a frame adapted to be supported on a baler, a plurality of wire tying members on the side of said frame toward said baler, each including a driven gear having an axially projecting hub, a bearing on said frame in which said hub is journaled, said driven gear, said hub and said bearing providing notches registering in one position of said gear and hub, means for locating said gears with said notches in registering position, wire holding means fixed in relation to said frame spaced outwardly from the bearings beyond the ends of the notched hubs and each arranged to hold a plurality of substantially parallelly arranged wires, and wire extracting means shiftable relatively to said frame, having a portion extending lengthwise of said frame disposed to engage all of said wires between said bearings and said wire holding means to force them in a direction to remove them from said notches, a guide portion slidable relatively to said frame to which the first-mentioned portion is attached, and said wire extracting means having a manually engageable actuating portion fixed to said guide portion on the other side of said frame as related to said driven gears, said hubs, said bearings, and said wire holding means.

7. A wire splicing device for use with a baler for tying the binding wires about the resulting bales comprising a frame composed of spaced-apart elongated frame portions and adapted to be supported on a baler, a toothed rack extending lengthwise of said portions, a driving gear engaged with said rack at one end of said frame, means for rotating said driving gear, mechanism for guiding said rack for movement lengthwise of said frame, a plurality of wire tying members spaced longitudinally of said frame portions on the side of said frame toward said baler, and each including a driven gear engaged with said rack for rotation by reason of lengthwise movement of said rack caused by rotation of said driving gear, each of said driven gears having an axially projecting hub, a bearing on said frame in which said hub is journaled, said driven gear, said hub and said bearing providing notches registering in one position of said gear and hub and opening toward said baler for reception of a plurality of substantially parallelly arranged wires, means for locating said rack and gears with said notches in registering position, wire holding means fixed in relation to said frame spaced outwardly from the bearings beyond the ends of the notched hubs and adapted to hold said plurality of wires for twisting between said holding means and said driven gear, and wire extracting means shiftable relatively to said frame, having a portion disposed to engage a wire between said bearing and said wire holding means to force it toward said baler to remove it from said notch, and said wire extracting means having a manually engageable actuating portion on the other side of said frame as related to said driven gear, said hub, said bearing, and said wire holding means.

8. A wire splicing device for use with a baler for tying the binding wires about the resulting bales comprising a frame composed of spaced-apart elongated frame portions, a toothed rack

extending lengthwise of said portions, a driving gear engaged with said rack at one end of said frame, manually operable means for rotating said driving gear, mechanism for guiding said rack for movement lengthwise of said frame, a plurality of wire tying members spaced longitudinally of said frame portions and each including a driven gear engaged with said rack for rotation by reason of lengthwise movement of said rack caused by rotation of said driving gear, each of said driven gears having an axially projecting hub, a bearing on said frame in which said hub is journaled, said driven gear, said hub and said bearing providing notches registering in one position of said gear and hub for reception of a plurality of parallelly arranged wires, means for locating said rack and gears with said notches in registering position, wire holding means fixed in relation to said frame spaced outwardly from the bearings beyond the ends of the notched hubs and adapted for holding said wires for twisting between said holding means and said driven

5 gears, and wire extracting means shiftable relatively to said frame, having a portion disposed to engage a wire between said bearing and said wire holding means to force it in a direction to remove it from said notch, and said wire extracting means having a manually engageable actuating portion on the other side of said frame as related to said driven gear, said hub, said bearing, and said wire holding means.
